ATTORNEY

UNITED STATES PATENT OFFICE.

ROBERT LEE ARMSTRONG, OF LINCOLN, NEBRASKA.

HOLDER FOR SAFETY-RAZOR BLADES.

Application filed June 21, 1924. Serial No. 721,460.

To all whom it may concern:

Be it known that I, ROBERT L. ARMSTRONG, a citizen of the United States, residing at Lincoln, in the county of Lancaster and State of Nebraska, have invented a new and useful Improvement in Holders for Safety-Razor Blades, of which the following is a specification.

This invention relates to holders for safety razor blades.

The object is to provide means for holding the blades of safety razors of the double cutting edge type in a manner to avoid injury to the hands of the operator and damage to the blades while the latter are being honed, stropped or otherwise sharpened, in the same manner as the old type of razor.

Another object is to provide a simple, strong and durable holder for the purpose, which may be easily and quickly opened for the reception of the blade, and as easily closed and clamped to retain the same in position during the required manipulations while sharpening, the holder being also useful for the utilization of cast off razor blades to be used by seamstresses, etc., in ripping seams and for many other analogous uses.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claim.

In the drawing, in which similar reference characters designate corresponding parts throughout the several figures:

Figure 1 is a side elevation of the improved holder with the razor blade clamped in position;

Figure 2 is an elevation of the reverse side thereof, the handle being broken away and shown in section;

Figure 3 is a longitudinal section through the same;

Figure 4 is an end view of the holder and blade;

Figure 5 is a perspective view of the members comprising the clamping and supporting means.

Referring to the drawing, there is shown a base plate 1, formed of suitable thin metal capable of being nickel plated, as are all parts of the device. The base plate is of elongated, substantially rectangular form, the ends 2 being rounded, as shown, to conform to the shape of the razor blades commonly used in safety razors, the base plate being somewhat longer than the blade. One longitudinal side edge of the base plate is provided with an integral, overhanging flange 3 which constitutes a seat or guard for one cutting edge of the razor blade 3^a, the outer edge of the said flange being rounded to provide a rolling edge for the device in turning the same over on a strop or hone, during the operation of sharpening the blade in the ordinary, well-known manner.

One rounded end edge of the base plate is provided with a centrally-located notch or recess 4 for a purpose to be explained, and the opposite end of the base plate is provided with a longitudinally extending shank 5, arranged substantially in the center of the plate 1, and suitably secured to the side thereof opposite to the flange 3, the said shank being of half-round shape in cross section and extending nearly to the notch 4, as clearly shown in Figure 2 of the drawing.

The shank 5 is provided with a recess 5^a for the reception of the base plate 1 so that the upper surface of the latter and the upper, flat side of the shank will be flush, and the two members may be brazed or riveted together as desired. The outer free end of the shank 5 is reduced as at 6 to provide a shoulder 6^a, and the said reduced portion, which is also half-round in cross section, is provided with threads, or the threads may be omitted.

Outstanding bosses or lugs 7 are formed on the upper or inner face of the base plate 1, and substantially at the longitudinal center line thereof, the said lugs being properly shaped and spaced apart to enter the holes 7^a provided in the razor blade, and serving to hold the same from movement in the holder, after the clamping means, to be described, has been applied.

Co-acting with the base plate 1 and the parts carried thereby, is a clamping bar 8,

which is also half-round throughout the major portion of its length and of the same diameter as the aforesaid shank 5, the said bar extending the full length of the base plate 6 and shank and somewhat beyond the terminal portion 6 of the latter, the flat side 9 of said bar being adapted to rest upon the razor blade 3^a and to hold the same in position when applied in a manner to be de-

10 scribed.

The clamping bar 8 has one end slightly tapered and provided with a hook 10 which is adapted to fit in the aforesaid notch 4 of the base plate, and at the other end the same 15 is reduced, as at 11, to provide a shoulder 8^a corresponding to the shoulder 6^a, the length of the flat face 9 of the bar being such as to receive the base plate 1 and the shank 5 carried thereby, when the hook 10 20 is engaged in the notch 4. Beyond the adjacent end of the flat face 9, the reduced end 11 of the clamping bar is round in cross section and is threaded from the aforesaid shoulder 8^a to a point adjacent to the outer 25 terminal thereof, as clearly shown in Figure 5 of the drawing.

The clamping bar 8 is further provided with spaced recesses 12 which receive the ends of the lugs or bosses 7 where they project slightly through the razor blade 3^a (see Figure 3), when the latter is properly placed between the base and the clamping bar.

A tubular metal handle 13, having suitable 35 internal threads, is adapted to be screwed onto the extending, reduced end 11 of the clamping bar and the same may remain in threaded connection therewith at all times. The outer surface of the handle 13 is preferably knurled in the usual manner to facilitate turning the same, and at the open end of the threaded bore therein, the handle is 40 preferably provided with a conical mouth 14.

In applying a blade to be stropped or 45 honed or for other purposes, the said blade is placed upon the base plate 1 with one of the cutting edges engaged beneath the overhanging flange or guard 3 and the bosses 7 fitting in the holes 7^a of said blade. The 50 clamping bar 8 is positioned over the said bosses, and the hook 10 engaged in the notch 4 of the base plate. When the two members are pressed together, the blade is securely 55 clamped and the end of the reduced portion 6 of the shank fits in substantial abutting relation to the end of the flat face 9, and the co-acting threads of the two halves form a continuation of the threads of the extension 11, and the handle may be screwed up 60 onto the same, the aforesaid conical mouth 14 serving to align the members. By fur-

ther screwing action thereof until the end of the handle abuts against the shoulders 6^a and 8^a, the blade is firmly held in position. In removing the blade it is only necessary 65 to unscrew the handle to a point slightly beyond the end of the reduced portion 6 of the shank 5, as will be apparent, the handle remaining on the terminal threaded portion of the clamping bar.

70 From the foregoing it will be seen that a simple, cheaply-manufactured and strong and durable holder for safety razor blades has been provided, which will permit of stropping or honing said blades in the manner ordinarily employed in sharpening the old style razor, and that the device may also be employed in holding such razor blades when discarded for shaving purposes, and thus make possible the continued use of the 75 same for other purposes.

What is claimed is:

A holder for safety razor blades having 80 holes therein comprising a substantially rectangular base plate provided with integral lugs adapted to traverse said holes in the blade, and an integral overhanging rounded flange which constitutes a guard along one edge to receive one cutting edge of said 85 blade, said base plate having a centrally located notch at one end, and a longitudinal, substantially half round shank projecting from the other end, said shank extending longitudinally and centrally along the base plate toward but spaced from said notch and formed integral with the base plate to reinforce and stiffen the same, a substantially half round rigid clamping bar having 90 its flat side adapted to bear on the blade and provided with recesses on the flat side to receive said lugs, said bar having a hook at 95 one end to engage said notch in the base plate, the clamping bar extending the full length of the base plate and shank but of materially less width than the base plate and having a full round terminal portion 100 provided with threads, the said half round projection of the shank interfitting and abutting the said terminal portion of the said bar and having aligned external shoulders and a tubular one piece handle internally threaded to screw onto the terminal portion of the clamping bar and also engage the said projection of the shank and having a conical mouth at its inner threaded end to 105 align the said parts and engage said shoulders.

In testimony, that I claim the foregoing as my own, I have hereto affixed my signature.

110

ROBERT LEE ARMSTRONG.
